(57) **CLAIM**

The ornamental design for security network handset controls, substantially as shown and described.

DESCRIPTION

FIG. 1 is a perspective view of the ornamental design for the security network handset controls;

FIG. 2 is a front view of the ornamental design for the security network handset controls;

FIG. 3 is a rear view of the ornamental design for the security network handset controls;

FIG. 4 is a left side view of the ornamental design for the security network handset controls;

FIG. 5 is a right side view of the ornamental design for the security network handset controls;

FIG. 6 is a top view of the ornamental design for the security network handset controls; and,

FIG. 7 is a bottom view of the ornamental design for the security network handset controls.

The broken line showing of environmental structures is for illustrative purposes only and forms no part of the claimed design.
